UNITED STATES PATENT OFFICE.

CHARLES J. SOLI, OF RACINE, WISCONSIN, ASSIGNOR OF ONE-HALF TO CHARLES A. SOLI, OF RACINE, WISCONSIN.

WINDOW.

1,199,022.

Specification of Letters Patent. Patented Sept. 19, 1916.

Application filed September 28, 1914. Serial No. 863,818.

To all whom it may concern:

Be it known that I, CHARLES J. SOLI, a citizen of the United States, and resident of Racine, in the county of Racine and State 5 of Wisconsin, have invented certain new and useful Improvements in Windows; and I do hereby declare that the following is a full, clear, and exact description thereof.

My invention refers to slidable and swing- 10 ing windows and has for its object to provide a simple, economical and effective glass-carrying frame that is removably fitted into the slidable window sash, whereby the glass within the frame can be conveniently re- 15 moved for cleaning upon both sides, within an apartment. Thus the danger and incon- 20 venience incidental to washing windows of the ordinary slidable type upon the outside is dispensed with.

Other objects of my invention are to 25 provide a glass-carrying frame that is pref- 30 erably in hinge connection with the slid- 35 able sash, whereby the sash can be swung inwardly for the purpose above men- 40 tioned; to provide a simple and economical weatherproof joint between the lower glass- 45 carrying frame rail and corresponding rail of the slidable sash member, and to provide a simple and effective strip for securing the 50 glass within the frame having an interposed yieldable filler between the strip and glass, 55 whereby the said glass is held tightly and cushioned. By this construction the glass may readily be renewed without the assist- 60 ance of a skilled glazier.

With the above and other minor objects in view the invention consists in certain pecularities of construction and combina- 65 tion of parts as set forth hereinafter with 70 reference to the accompanying drawings and 75 subsequently claimed.

In the drawings Figure 1 represents a 80 sectional elevation of a window embodying the features of my invention, the section 85 being indicated by line 1-1 of Fig. 2, with one of the window members shown swung inwardly; Fig. 2, a face view of the same; Fig. 3, an enlarged detailed cross-section taken on the line 3-3, Fig. 2, showing cer- 90 tain preferred modifications of construction, and Fig. 4, a detailed cross-section through the side jambs and window, taken on the line 95 4-4, Fig. 2, showing the desired construc- 100 tion wherein hinges are employed.

Referring by characters to the drawings, 55 1, 1, represent the side jambs of a window casing provided with the usual spaced sash-bars between which the upper and lower window members are adapted to slide in the usual manner. Both the lower and upper 60 window members comprise slidable sashes 3 having inwardly projecting flanged strips 4, which flanged strips, in conjunction with the inner faces of the slidable frames, form countersunk seats for the supplemental 65 frames 5. These supplemental frames are fitted with panes of glass 5' that are secured by clencher rails 6 upon three sides and a base clencher rail 6', which clencher rail, in conjunction with the bottom of the frame 5, 70 constitutes an overhanging weather-shedding strip. This weather-shedding strip, as best shown in Fig. 3 of the drawings, projects over and beyond the bottom flanged strip 4, the upper edge of which bottom 75 flanged strip is beveled inwardly, as shown, whereby the joint is protected. Thus water dripping from the upper face of the strip 6' will be deflected by the beveled edge of the strip 4, whereby leakage to the interior 80 of the compartment is avoided. This construction is also utilized in connection with the upper window member for the same purpose. Each supplemental frame is preferably connected to its sliding frame 3 by 85 hinges 7, the said frames being adapted to swing inwardly, whereby the supplemental frames can readily be removed from the sashes for cleaning purposes without removing said sashes. In instances where the 90 supplemental frames 5 are hinged to the sashes, a button 8 or other suitable fastening device may be employed for securing said frames when they are closed with relation 95 to the sashes.

It is obvious that, while I have shown and described the supplemental frames as being preferably in swinging connection with the sashes, I may, without departing from the spirit of my invention, simply fit the supplemental frames into place and fasten the same by buttons or other suitable confining means. In this instance the frames can be entirely removed from their sashes.

As best shown in Figs. 3 and 4, the window panes 5' may be secured to the supplemental frames 5 by the clencher rails 6, 6', which rails are fastened by screws or the

like. Interposed between the rails and adjacent face of the panes of glass are cushion strips 6", whereby the joint is more effectively closed, while at the same time, the 5 said panes of glass are held tightly against liability to rattle. This arrangement of fastening the panes dispenses with putty and is particularly desirable for replacing broken panes of glass without the aid of 10 glaziers.

From the foregoing description it will be seen that the essential feature of my invention is the arrangement of a supplemental frame within a window so connected that 15 the glass-carrying frame can be swung inwardly for the convenience of the housewife in cleaning. Thus both sides of the panes of glass are accessible within the apartment or room for the purpose specified and when 20 the glass is thoroughly polished all that is necessary is to swing the same to their closed positions and the windows are then, to all appearances, of the ordinary type and the

joint about the swinging supplemental frames is absolutely weatherproof. 25

I claim:

A sash frame having a rabbet on the inner upper corner of the lower rail, a supplemental sash seated in said rabbet and having in the outer upper edge of its lower 30 rail a rabbet, the bottom of which is substantially in the plane of the upper face of the outer flange of the lower rail of the sash frame, a pane in the rabbet of the supplemental sash, and a retaining strip for the 35 pane seated in the rabbet and of sufficient width to project outward beyond the upper edge of the flange of the sash frame.

In testimony that I claim the foregoing I have hereunto set my hand at Racine in 40 the county of Racine and State of Wisconsin in the presence of two witnesses.

CHAS. J. SOLI.
